UNITED STATES PATENT OFFICE.

EDWARD L. BRONSTIEN, OF ST. PAUL, MINNESOTA.

ATTACHMENT FOR BED SPRINGS.

Application filed April 13, 1926. Serial No. 101,770.

This invention relates to attachments for bed springs and it is an object of the invention to provide an attachment especially designed and adapted for use in connection with a bed spring provided with a frame and a border wire for the fabric and which acts as a stabilizer for the border wire, assuring such wire returning to its normal or original position when the spring or more particularly the fabric is free of strain.

The invention consists in the details of construction and in the combination and arrangement of the several parts of my improved attachment for a bed spring whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:—

Figure 1 is a view partly in section and partly in elevation illustrating an attachment constructed in accordance with an embodiment of my invention, a second position of certain of the parts being indicated by broken lines;

Figure 2 is a view in top plan of the attachment as illustrated in Figure 1, the adjacent portions of the spring proper being fragmentarily indicated by broken lines;

Figure 3 is a view in top plan of the body or attaching member of the attachment unapplied;

Figure 4 is a sectional view taken substantially on the line 4—4 of Figure 1.

As disclosed in the accompanying drawing, my improved attachment comprises a body member B substantially U-shaped in cross section and having its side members or walls 1 in spaced relation and gradually decreasing in height from one end of the member B to the other. The upper marginal portions of the walls 1 are defined by the outstanding flanges 2 serving to strengthen said body member B, said flanges 2 having extensions 3 disposed beyond the high end of the walls 1 and adapted to rest from above upon a side member 4 of the bed spring. These extensions 3 are provided with the openings 5 whereby the body mem-

ber B may be riveted or otherwise positively secured to the member 4.

The base portion of the body member B at its high end is extended, as at 6, each of the extended side wall portions 1' being provided in its upper marginal portion immediately adjacent to the side wall 1 proper with an upwardly facing open recess 7 which is adapted to receive the lower marginal portion of the depending flange of the member 4 when the body member B is in applied position whereby said body member B is effectively maintained in applied or working position.

Extending between the side walls 1 adjacent to the high end of the body member B is a rigid arm 8 held in applied position by a rivet 9 or the like disposed through the side walls 1 and the arm 8. The lower or inner end of the arm 8 has direct contact with the intermediate or base portion of the body member B whereby said arm 8 is effectively held against rocking movement about its connection 9.

The opposite end portion of the arm 8 extends outwardly beyond the side walls 1 of the body member B, as is particularly illustrated in Figure 1, and attached, as at 10, to said outer end portion of the arm 8 is an extremity of a retractile coil spring 11. The opposite end portion of this spring is attached, as at 12, to the upper portion of a rigid link 14. This link 14 extends between the side portions of the walls 1 of the body member B at their outer or low portions and is pivotally engaged with the rivet 15 or the like interposed between and carried by the side walls 1.

The outer end portion of the link 14 is pivotally connected, as at 16, between the side walls 17 of an elongated member M. This member M is in cross section substantially in the form of an inverted U and the outer extremity of the intermediate portion 18 thereof is provided with an extended tongue 19 which is adapted to be disposed around the border wire 20 of a bed fabric of a type commonly in use. The outer end of the link 14 at its outer marginal portion is provided with an outstanding lug 21 with which the adjacent end of the intermediate portion 18 of the member M constantly abuts when the device is in applied or working position.

As pressure or strain is imposed upon

the bed fabric and as the border wire 20 has a tendency to move downwardly, the member M will have an inward oscillating movement to a position substantially indicated by broken lines in Figure 1 and with the link 14 having swinging movement inwardly of the bed fabric against the tension of the spring 11. When such pressure or strain is released, the spring S, which is constantly urging the link 14 in an opposite direction, will assure the border wire 20 returning to its normal or original position. By this means, the life of the spring is materially prolonged and at the same time assuring the maintenance of its original style or shape.

In practice, any number of my improved attachments may be employed but I find that good results can be obtained by applying one of the attachments to each of the side rails 4 of the frame proper at substantially the longitudinal center thereof. When so arranged, it will be understood that one of the devices coacts with the other in a manner to effectively eliminate side movement or rocking of the bed fabric and thus increase the efficiency of the bed spring.

When the attachment is applied, it is also to be understood that the member B extends inwardly from the associated side rail 4.

From the foregoing description it is thought to be obvious that an attachment

for a bed spring constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

In combination with a bed spring including a frame and a top border wire, a member secured to the frame and extending laterally therefrom, said member being in cross section substantially U-shaped, an arm fitting within said member and secured thereto, an end portion of the arm having direct abutting contact against the bottom of the U-shaped member to hold the arm against rocking movement, a link pivotally connected with said member, a retractile spring interposed between and secured to the arm and link, and an elongated member having one end portion secured to the border wire and its opposite end portion pivotally connected with the link.

In testimony whereof I hereunto affix my signature.

EDWARD L. BRONSTIEN.
